UNITED STATES PATENT OFFICE.

THEODORE B. GANONG AND HOWARD H. MEAD, OF QUINCY, MICHIGAN.

RACK FOR ROLLS OF MATERIAL.

Application filed September 8, 1924. Serial No. 736,583.

To all whom it may concern:

Be it known that we, THEODORE B. GANONG and HOWARD H. MEAD, citizens of the United States, residing at Quincy, in the county of Branch and State of Michigan, have invented certain new and useful Improvements in Racks for Rolls of Material, of which the following is a specification.

This invention relates to devices for supporting material in rolls, such as screen material and the like, in convenient position for storage and inspection, and has for one of its objects to improve the construction and increase the efficiency and utility of devices of this character.

Another object of this invention is to provide a simply constructed support for a roll of material having means whereby the roll is held from rotation on the support.

With these and other objects in view the invention consists in certain novel features of construction as hereinafter shown and described and then specifically pointed out in the claim, and in the drawings illustrative of the preferred embodiment of the invention—

Figure 1 is a side elevation, and

Figure 2 is an end elevation, of the improved device.

Figure 3 is a sectional elevation on the line 3—3 of Figure 2, looking in the direction of the arrow.

Figure 4 is a transverse section on the line 4—4 of Figure 3, looking in the direction of the arrow.

Figure 5 is a plan view with the supporting frame in section on the line 5—5 of Figure 3.

The improved device may be adapted without material structural change to support any class of material which is furnished in rolls, such as window and door screen material, chicken run material, some forms of fencing, and the like, but is designed more particularly for supporting rolls of window screen material in convenient position for storage and display and so arranged that the supports for the rolls may be individually inserted and removed, or so that one or more rolls may be inserted or removed without disturbing the remaining rolls.

In its simpler form the improved device comprises terminal supports each formed with a lower transverse member 10, an upper transverse member 11, and a plurality of

vertical division members 12 connected at their ends to the transverse members, as shown.

One of the frame structures is inclined inwardly and upwardly, as shown, to provide for supporting rolls of material of varying lengths, as hereinafter explained.

The members 10 and 11 may be of any required length to accommodate any required member of the vertical division members 12, but for the purpose of illustration three of the division members are shown.

Connected at their ends to the division members 12 are spaced horizontal rails 13, each confronting pair of the rails forming spaced guide tracks between the confronting faces of the vertical division members 12.

Each pair of the rails and the vertical members thus provide a separate pocket or receptacle, as indicated more particularly in Figures 2 and 4.

Slidably disposed in each of the pockets or receptacles, is a holder or carrier for a roll of material, but as the holders are alike except as to length, the description of one will suffice for all.

Each holder or carrier comprises a frame formed with vertical side members 14 and vertical end members 15, each of the end members having an upwardly opening socket 16. Attached to the lower edges of the end members 15 is a support 17. Each of the members 17 is in alignment horizontally with the guide rails 13 and laterally enlarged at one end as at 18 to slidably engage the confronting faces of the rails 13, as represented more clearly in Figure 5, and thus operate as wear elements, to slidably engage the confronting faces of the tracks 13, and hold the sides 14 of the holders from contact with the vertical dividing members 12. The friction between the parts is thus materially reduced and the wear between the parts correspondingly reduced.

The sockets 16 are designed to receive the journal 19 of a roller 20, the latter to support a roll of material, as indicated at 21. One of the journals 19 is extended into a turning handle 22.

Extending from each of the rollers 20 are short pins 23 adapted to be engaged with the inner end of each roll, to lock the latter to the roller, to insure the rotation of the roll of material with the roller when the latter is operated.

Window and door screen material and the

like is manufactured and furnished to the trade in varying widths, and by arranging one of the terminal frames in an inclined position provision is made for supporting 5 holders or carriers and rolls of these varying lengths without waste of space.

Each of the holders or carriers together with its roll of material is independently removable from and insertible in the frame 10 when a portion of the material is to be reversed and sold, and the unsold portion returned to the frame.

Attached to the outer edges of one series 15 of the members 12, are stops 24, to limit the movement of the roll holder in one direction.

The improved device is simple in construction, can be inexpensively manufactured, of any size or capacity, and of any 20 suitable material or combinations of materials.

The preferred embodiment of the invention is claimed in the drawings and set forth in the specification, but it will be understood 25 that modifications within the scope of the claimed invention may be made in the con-

struction without departing from the principle of the invention or sacrificing any of its advantages.

Having thus described our invention what 30 we claim is:

A device of the class described comprising vertical terminal frames, guide rails connected at the ends to said frames with their confronting edges in spaced parallel relation, supports for material including vertical sides and ends, said sides slidably engaging said rails, and a longitudinally directed lower member attached at the ends 35 to the vertical ends of the material support and depending below the line of the ends and sides thereof and between said guide rails, said lower member being laterally enlarged at the ends to movably engage the confronting edges of the guide rails, and 40 preventing lateral displacement of the material holder.

In testimony whereof, we affix our signatures hereto.

THEODORE B. GANONG.
HOWARD H. MEAD.
